UNITED STATES PATENT OFFICE.

GEORGE LESLIE FORT, OF DES MOINES, IOWA, ASSIGNOR TO FORT-IFIED MANUFACTURING COMPANY, OF KANSAS CITY, MISSOURI, A CORPORATION OF MISSOURI.

TYPE-METAL AGITATOR.

1,363,402.

Specification of Letters Patent. Patented Dec. 28, 1920.

Application filed November 1, 1919. Serial No. 335,064.

To all whom it may concern:

Be it known that I, GEORGE L. FORT, a citizen of the United States, residing at Des Moines, in the county of Polk and State 5 of Iowa, have invented certain new and useful Improvements in Type-Metal Agitators; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to a type-metal agitating device which may be used for mixing a metal batch so that a uniform quality of metal may be maintained. As an example of the use to which the invention 20 may be put, attention is directed to the fact that in newspaper and publishing offices the type-metal is cast in stereotyped plates to be used in a printing press sometimes for a single edition. The stereotyped plates are 25 then remelted for subsequent use. The remelted metal must sometimes be mixed with metal which has not been cast or sometimes the batch of type-metal must be supplied with a suitable rejuvenating chemical (or in a nomenclature of the compositor, a suitable 30 "dope" is added). When this is done, the so-called "dope" is liable to be localized in the large batch of type-metal with the result that the metal is not of uniform quality and 35 therefore objectionable.

I have provided means whereby the metal may be caused to become agitated so that all of its component constituents will become thoroughly commingled to form a substantially homogenous mass of uniform quality.

40 My invention contemplates a steam generator comprising a receptacle which may contain a suitable liquid, the receptacle being adapted to be emersed in the melted type-metal so that the heat thereof will convert the liquid into steam and cause it to escape from the receptacle in the body of type-metal so as to cause an effective agitation thereof.

45 In the drawings,

Figure I is a vertical longitudinal sectional view of a steam generator constructed in accordance with my invention.

Fig. II is a fragmentary perspective view of a type pot to which my invention has been applied, and

Fig. III is a cross sectional view on the line III—III of Fig. II.

Referring now to the drawings by numerals of reference:

1 designates a receptacle which, for convenience, may be cylindrical in form, with an inlet opening 2 at one end and an outlet opening 3 in the other. The outlet opening may be provided in a plug 4 which may 65 initially be screwed into the cylinder 1 and fastened thereto by autogenous welding. The opening 3 is surrounded by a tubular member 5 having an opening 6 in the top thereof and steam outlet openings 7 in the 70 side wall. Within the tube 5 is a spider 8 serving as a guide for the valve stem 9 of the needle valve 10 which is adapted to close the opening 3. The valve stem 9 extends through the opening 2 and projects a considerable distance beyond the receptacle 1 so that the valve wheel or handle 11 will be 75 accessible externally from the type-metal pot 12 containing the type-metal 13.

Surrounding the opening 2 of the receptacle 1 is a threaded flange 14 which carries a sleeve 15 having a safety vent or port nozzle 16 in the wall thereof. The upper end of the tubular member 15 is threaded to receive a plug 17 forming part of the end wheel 18 80 adjacent to the handle 11. The plug 17 carries a yoke 19 which is provided with an inwardly projecting flange 20 movable in the space 21 between the flanges 22 and 23 on the tubular valve stem 24, which is sleeved 90 upon the valve stem 9. The lower end of the valve stem 24 carries a valve 25 which normally closes the opening 2 which, as will be observed, is considerably larger than the valve stem 9. The upper end of the valve 95 stem 24 abuts against the expansion spring 26 which is interposed between the upper end of the stem 24 and the lower end of the plug 17, its normal tendency being to maintain the valve 25 upon its seat the scale of 100 the spring being such, however, that a given steam pressure in the receptacle 1 above the water level 27 will raise the valve 25 and permit the escape of steam through the exhaust 16.

105 Assuming all of the parts to be assembled

and it is desired to introduce a liquid such as water in the receptacle 1, the plug 17 will be unscrewed by the handle 18 so that the stem 9, the sleeve 24, the valve 25, the spring 26 and yoke 19 may all be removed from the sleeve 15 and the receptacle 1. The liquid may then be poured into the tubular member 15 until a sufficient amount has entered the receptacle 1 whereupon the mechanism just removed will be re-positioned, the valve 10 may then be seated to close the opening 3 by turning the valve stem 9 so that the spring 26 causes the valve 25 to close the opening 2. If it is desired to cause agitation of the type-metal, the receptacle 1 may be introduced therein, as shown in Fig. II and if desired, held by the clamp 28. The heat of the metal 13 will cause steam to be generated in receptacle 1 by turning the valve stem 9 through the medium of its handle or wheel 11, the valve 10 will be unseated from the seat of exhaust opening 3 so that the steam generated in receptacle 1 may pass through the opening 7 and escape through the opening 3. The escape of the steam into the body of the metal will cause a violent bubbling or agitation so that the contents of the pot 12 will be thoroughly mixed. If, for any reason, the valve 3 becomes stuck or should the type-metal clog the opening 3 so as to prevent an escape of the steam generated, the pressure would build up in the receptacle 1 enough to lift the valve 25 against the action of spring 26 and permit the escape of the steam through the safety nozzle 16 and thereby prevent an explosion due to pressure in receptacle 1. When the type-metal 13 has been sufficiently agitated, the device can be removed for subsequent use.

From the foregoing it will be apparent that the device is simple in construction, that it may be readily applied in a type pot and that the amount of steam passing into the type-metal may be controlled by the handle 11 on stem 9.

Having thus described my invention, what I claim as new therein, and desire to secure by Letters-Patent is:

1. In a device for agitating molten type-metal, a steam generating receptacle insertible within the body of the metal, a pressure-valve controlling discharge port above the level of the metal, and a manually-operable valve-controlled discharge port below the surface of the metal.

2. In a device for agitating molten type-metal, a steam generating chamber insertible within the body of metal, a pressure-valve controlled discharge above the metal,

and means for discharging steam below the surface level of the body of metal.

3. In a device for agitating molten metal, a steam generating receptacle insertible within a body of metal, a valve discharge port in the steam generating chamber, and means, exteriorly of the steam generating chamber and normally above the level of the body of metal, for controlling a valved discharge port.

4. In a device for agitating molten type-metal, a steam generating receptacle comprising a chamber containing liquid, the walls of the chamber being designed to absorb the heat from the molten metal to generate the liquid and the steam, a discharge port in said chamber, a valve for controlling the effective port area thereof, and means, normally above the body of type-metal, for operating said valve.

5. In a device for agitating molten type-metal, a steam generating chamber having a discharge opening at one end, a tubular handle connected to the other end surrounding an inlet opening in said chamber, a valve stem projecting through the tubular handle and into the chamber, a valve on the end of the stem for controlling the effective port area of the discharge opening, and a valve for closing the inlet opening in said chamber.

6. In a device for agitating molten type-metal, a steam generating chamber having a discharge opening at one end, a tubular handle connected to the other end surrounding an inlet opening in said chamber, a valve stem projecting through the tubular handle and into the chamber, a valve on the end of the stem for controlling the effective port area of the discharge opening, and a pressure valve for closing the inlet opening in said chamber.

7. A device for generating steam to agitate molten type-metal comprising a chamber having an inlet port at one end and an outlet port at the other end, a valve stem projecting through the inlet port, a valve carried by said stem for controlling the effective port area of the outlet port, a tube surrounding the inlet port and valve stem, said tube being of appreciable length to provide a handle for the chamber, a spring-pressed sleeve on the valve stem, a valve carried thereby for normally closing the inlet opening, a discharge port carried by the sleeve, and a plug closing the open end of the tube, the plug being connected to the sleeve and surrounding the valve stem.

In testimony whereof I affix my signature.
GEORGE LESLIE FORT.
